Des. 192,730
Patented May 8, 1962

192,730

AUTOMOBILE WHEEL COVER

George K. Bishop, Dearborn, Mich., assignor to Chrysler Corporation, Highland Park, Mich., a corporation of Delaware

Filed Feb. 27, 1961, Ser. No. 64,065

Term of patent 7 years

(Cl. D14—30)

Des 192,730

PAGE 2

FIG. 1

FIG. 1 is a front elevational view of an automobile wheel cover showing my new design;

FIGS. 2, 3, and 4 are sectional views taken on the lines 2—2, 3—3 and 4—4, respectively, of FIG. 1; and

FIG. 5 is a perspective view of the automobile wheel cover shown in FIG. 1.

I claim:

The ornamental design for an automobile wheel cover, substantially as shown.
